REEL FOR PICTURE MACHINES

Joseph K. E. Sunell, Hempstead, N. Y., assignor of forty-nine per cent to Dominick Santora, Hempstead, N. Y., and twenty-five and one-half per cent to Emil Nikolaus Nilsson, Franklin Square, N. Y.

Application June 7, 1938, Serial No. 212,343

5 Claims. (Cl. 88—18.7)

My invention relates to moving picture machines, and more particularly to the reels thereof, by means of which the film is quickly and effectively fed from one reel to the other. It applies more especially to the lower reel into which the film is fed and from which it may be removed to the upper.

The object of the invention is to enable the operator, when the winding is completed, to remove the film from the lower reel and transfer it to the upper magazine. A further object is to produce a device that can be easily and cheaply manufactured and readily manipulated.

In the drawings forming a part of this specification, and in which like symbols of reference represent corresponding parts in the several views:

Figure 1 is a side elevation of a projection machine embodying my invention;

Figure 2 is an enlarged view, partly in elevation and partly in section, showing the lower magazine and a portion of the upper magazine.

Figure 3 is an enlarged section on the line 3—3 of Figure 1;

Figure 4 is a section on the line 4—4 of Figure 3 to illustrate disk 15 merely, the apertures and other parts not shown, and the casing entire;

Figure 5 is an enlarged section on the line 5—5 of Figure 3, with the casing and other parts omitted, to illustrate a slotted plate 18 used in the device;

Figure 6 is a greatly enlarged fragmentary section, of a modification, on the line 6—6 of Figure 3, showing the opposite side of the plate shown in Figure 5;

Figure 7 is a fragmentary section on the line 7—7 of Figure 6, with parts broken away; and

Figure 8 is a fragmentary detail showing a modification of the device shown in Figure 3.

The projector of the device, 10, is of the usual form, and is provided with an upper magazine 11, and a lower magazine 12. Each magazine has an access door, these being indicated at 13 and 14 respectively. In the lower magazine is mounted a fixed disk 15 having a shaft receiving opening 16. The disk 15 is provided with radially extending slots 17. Fixed on the rear face of this disk is a circular plate 18 having a shaft opening 19 and slots 20 registering with the opening 16 and slots 17. On the rear face of this plate 18 is a series of pairs of Z-shaped confronting guides 21, the guides of each pair being located on opposite sides of a respective slot. Extending from the rear wall of the magazine 12 is a stub shaft 22 whereon is revolvably mounted

a sleeve shaft 23 which extends rotatably through the openings 16 and 19.

On the front end of the shaft 23 is fixed a revoluble disk 24 having a series of arcuate slots 25 extending from the central portion of the disk to points at the periphery thereof. The slots 25 correspond in number to the slots 17. Suitably mounted in the housing is a series of rollers 26, preferably three in number, spaced to receive a film drum, including a cylindrical band 27, carrying outwardly extending flanges 28 which ride on the rollers 26. The inner flange 28 has a ratchet 58' which rides on rollers 26.

Through each pair of registering slots 17 and 20 and through a corresponding slot 25 extends a shaft 29. Each shaft 29 carries a slide 29a which is mounted between a respective pair of guides 21 to slide therein. It will now be noted that the curvature of the slots 25 is such that movement of the shafts 29 inwardly of the disk 15 effects camming action on the plate 24 to cause it to rotate in the direction of the arrow A of Figure 2. On each shaft 29 at the front end thereof is mounted a flanged roller 30, the flanges being of grooved rubber which may be formed by a pair of flanged disks 31, as in Figures 6 and 7. Preferably there are sixteen of these rollers which are evenly spaced within the drum 27.

Fixed to the central portion of the disk 15 is a pair of rods 32 and 33 which pass through a slot 34 formed in the disk 24 concentric thereto. There is also a third rod 35 which passes through an arcuate slot 36 formed in the disk 24 concentric thereto. The rods 32 and 35 have heads on each of which is mounted three anti-friction rollers 37. The rod 33 carries but two rollers 38, a guide 39 being arranged between them. The rods 32 and 33 have their outer ends within the drum 27, while the rod 35 extends forwardly of the drum and is inclined as shown in Figure 3.

The film F is led from the upper magazine 11 over a series of guide rollers 40 in the head 41 and upper part of the lower magazine 12, and passes to the rolls 37 on the rod 35, thence to the rolls 37 of the rod 32, thence between the rolls 38 and around one of the rolls 30. The drum 27 is split into halves which are hinged together at 42, and the end of the film F passes between the halves at 43 and is caught beneath a clip 44.

A shaft 45 is suitably journalled in the lower part of the magazine 12 and is drawn by a belt 46 deriving power from the motor of the projection machine which engages a pulley on said

shaft. On the forward end of this shaft is a pinion 48 which engages a gear 49 carried by the drum 27. The lower shaft 29 is extended rearwardly as at 50 and carries a belt pulley 51. Above the shaft 45 is a stub shaft 52 on which is mounted an idler pulley 53 alined with pulley 51. On the shaft 45 is fixed a pulley 54 alined with the pulley 53 and a belt 55 is trained around the pulleys 53 and 54 and engages the pulley 51. This causes the lower roller 30 to rotate as the shaft 45 is driven. Also, the rotation of the shaft 45 rotates the drum 27 and the rotation of the drum draws the film around the rollers 30 to lie in a tight coil within the drum at the periphery thereof, this action being assisted by the coaction between the lower rolls 30 and 26.

In the form shown in Figure 8 the shaft 52 may be used as a driving shaft, being itself drawn by the belt and pulley arrangement shown at 56. This is merely a reversal of the form shown in Figure 3, the power being imparted through belt 70, through pulleys 56 and band 71.

When all of the film has been wound within the drum the rolls 30 will have moved inwardly. These rolls are, during the start of operations, held from movement by a pawl 57 engaging a ratchet 58 on one of the flanges 28, a pull rod 59 being actuated to release the pawl after one or two convolutions of film have been wound within the drum. As the winding continues the slots 25 are cammed by the shafts 29 causing the disk 24 to turn. When the winding has been completed, the door 14 is opened and the disk 24 manually rotated to draw the rolls 30 inwardly clear of the coil of film. The drum and coil of film may now be removed from between the supporting rolls 26.

The film may now be removed from the drum by opening the latter slightly on the hinge 42 and the drum replaced for further winding. The reel coil of film may now be placed on a suitable reel ready for unwinding from its exterior in the usual manner.

In order to restore the shafts 29 to their normal outward positions a coil spring 23a has one end connected to the sleeve 23 and has its other end connected to a fixed post 23b. This tends to turn the cam disk against the direction of the arrow in Figure 2 and thus urges the shafts 29 outwardly.

Having now fully described my invention, what I claim as new, and desire to secure by Letters Patent, is:

1. A film winding device, comprising means for winding the film, consisting of a fixed disk formed with radial slots, a plate connected to the same and having slots registering with the forementioned slots, guides connected to the rear plate, a revoluble disk having arcuate slots corresponding with the forementioned slots, shafts extending through the slots, slides connected to the

shafts and operating in the guides, rollers also carried by the shafts, a drum within which the rollers operate, rollers supporting the drum, and a shaft journaled in the device and having engagement with the drum, said shaft having a pulley adapted to be connected to the power.

2. A film winding device, comprising means for winding the film, consisting of a fixed disk formed with slots, a plate connected to the same and provided with corresponding slots, guides connected to the second plate, a revoluble disk formed with arcuate slots registering with the slots of the fixed disk and plate, shafts extending through the slots, slides connected to the shafts and moving in the guides, rollers on the shafts, a film drum into which the rollers extend, and a drive-shaft having a pinion engaging a gear on the drum to operate the same.

3. A film winding device, a fixed disk having slots, a plate connected to the same and provided with corresponding slots, guides on the plate, a revoluble disk having arcuate slots, shafts carrying slides to move in the guides and having rollers on their inner ends, one of said shafts extending to the rear of the casing and adapted to be connected to power, a film drum in which the rollers operate to receive the film, a series of rollers supporting the drum, a pinion on the power shaft, and a gear on the drum engaging the pinion on the power shaft, so that when the film is wound within the drum the rolls will have moved inwardly and the film be transferred.

4. A film winding device, a fixed disk provided with slots and having a slot-provided plate connected to the same, guides on the plate, a revoluble disk having arcuate slots, shafts extending through the slots, guiding means for the same, rollers on the shafts, a film drum within which the rollers operate to receive a film, means for operating the drum, a plurality of rods connected to the fixed disk and passing through a slot formed in the revoluble disk and extending within the drum, and a third rod connected to the fixed disk passing through a slot in the revoluble disk and extending forwardly of the drum, said rods adapted to receive and guide the film.

5. A film winding device, a fixed disk provided with slots, a slotted plate connected to the same, said plate having guides in the same, a revoluble disk having arcuate slots registering with the slots of the fixed disk and plate, guides on the plate, shafts extending through the slots and provided with rollers on their inner ends, one of said shafts extending to the rear of the casing, a film drum within which the rollers extend and operate to feed the film, a drive-shaft having a pinion engaging a gear on the drum to operate the same, and connections between the drive-shaft and slot shaft at the end of the casing to cause them to coact as the film is fed.

JOSEPH K. E. SUNELL.
